ATTORNEYS

UNITED STATES PATENT OFFICE.

FERNANDO JOHN DERIFIELD, OF BOISE, IDAHO.

VALVE GRINDER.

Application filed January 18, 1922. Serial No. 530,221.

To all whom it may concern:

Be it known that I, FERNANDO JOHN DERIFIELD, a citizen of the United States, and a resident of Boise, in the county of Ada 5 and State of Idaho, have invented certain new and useful Improvements in Valve Grinders, of which the following is a specification.

This invention relates to improvements 10 in valve grinders, and is especially adapted for use in grinding valves of the overhead type which embody a valve and cage, such as are used upon the "Buick" automobiles.

The object of the invention is to provide 15 a valve grinder of this character in which the valve and its seat are subjected to such grinding action as will insure a uniform and complete grinding of the entire working surfaces of the valve and seat whereby perfect seating of the valve is brought about and wherein all of the phases of the valve grinding operation are automatically carried out.

Another object is to provide a valve 20 grinder of this character which is of simple and durable construction, reliable in operation and easy and inexpensive to manufacture and operate and which is adapted to meet varying requirements of this character 25 of work.

Other objects and advantages of the invention reside in certain novel features of construction, combination and arrangement of parts which will be hereinafter more 30 fully described and particularly pointed out in the appended claims, reference being had to the accompanying drawings forming part of the specification and in which:

Figure 1 is a plan view of the preferred 35 embodiment of the invention;

Figure 2 is a fragmentary view in side elevation;

Figure 3 is a detail perspective view of the rocking lever;

Figure 4 is a similar view of one of the 40 lift rods;

Figure 5 is a similar view of the rotating cam disk;

Figure 6 is a similar view of the lifting 45 toe;

Figure 7 is a similar view of the lifting fork; and

Figure 8 is a similar view of one of the 50 crank arms.

Referring to the drawings wherein for 55 the sake of illustration is shown the preferred embodiment of the invention, it will be seen that the valve grinder is of that type forming the subject-matter of my prior Patent No. 1,325,835. In the improved 60 construction which constitutes the present invention, there is provided a pair of standards, designated at 10 and 11, which up-stand from bases 12 and 13, the standards being preferably threadedly connected with 65 the bases. A frame 15 is mounted for sliding adjustment on the standards 10 and 11 and may be held in adjusted position thereon by means of set screws or the like which are preferably carried by the frame and engage- 70 able with the standards.

A plurality of vertical spindles, designated at 20 and 21 are rotatably journaled in bearings 22 and 23 provided therefor on the frame 11 and carry at their lower ends 75 chucks, designated at 24 and 25 which may be of any suitable type but which preferably are of the three jaw type of chuck. The chucks are adapted to engage a stem S of the valves V so that the motion of the 80 spindles is imparted to the valves and the valves on the other hand carry the cages C which as usual are tapered or reduced, as at c at their lower ends. These valves are the overhead type of valves such as used 85 on "Buick" motors.

Means is provided for imparting an oscillatory movement to the spindles 22 and 23 and preferably includes a crank arm 26 having a bearing portion 26^a at one end which 90 embraces and is fixed to the spindle 20. The outer end of the arm 26 is slotted as at 26^b and is pivotally connected with one end of a link 27 the opposite end of the link 27 being connected with a slotted end 28^a of the rock- 95 ing lever or arm 28 which is provided intermediate its ends with a bearing portion or hub 28^b by means of which it is secured or fixed to the upper end of the spindle 21. As shown in Figures 1 and 2 nuts designated at 100 29 and 30 are threaded on the upper ends of the spindles 20 and 21 and engage the upper surfaces of the bearing portions of the crank arm and crank, respectively. It is to be understood that suitable means is employed 105 for keying or fixing the bearing portion of the crank arm 26 and rocking arm 28 to the spindles 20 and 21, respectively. The end

of the rock arm 28 opposite the connection with the link 27 is slotted as at 28^c and this slotted end 28^c is suitably connected to one end of a connecting rod 31, the opposite end 5 of which is pivotally connected to a crank pin 32 carried by a driving pulley 33. The driving pulley 33 is actuated by belt gearing 34 from any suitable source of power and by means of the crank pin 32 and connecting rod 10 31 imparts rocking movement to the rocking arm 28. This rocking movement of the arm 28 oscillates the spindle 21 and through the link 27 and crank arm 26 also oscillates the spindle 20. In this manner oscillatory movement 15 is imparted to the valves V and such movement of the valve V will also result in movement of the valve cages C. With the construction so far described however uniform, complete and smooth grinding of the 20 valves will not always result as the valve V will tend to turn the cages C in one direction as well as in the other direction. In the present improved construction, it is proposed to provide means of a novel character and 25 highly organized with the mechanism above described for insuring relative rotation of the valve V and cages C while not impairing to any degree the grinding action between the cages and the valves. For this purpose a 30 plurality of lift rods designated at 40 and 41 is provided. One such lift rod is provided for each spindle and the lift rod of each spindle is disposed adjacent thereto. The upper ends of the lift rods 40 and 41 are bifurcated so as to provide long arms 42 and 44 and short arms 43 and 45, each lift rod having one long arm and one short arm as clearly shown in Figure 2. The arms of the bifurcated ends of the lift rods are journaled 35 for reciprocatory movement in the frame and downward movements of the lift rods are cushioned by means of coil springs 46 and 47 mounted on the arms 42 and 44 of the lift rods 40 and 41, respectively and engageable 40 with the frame at their lower end and with cotter pins 48 and 49 respectively at their upper ends. Adjacent the lower ends of the lift rods 40 and 41 lifting forks 50 and 51 are adjustably secured by means of 45 50 set screws 52 and 53, respectively. The arms of the lifting forks embrace the reduced portion c of the cages C and while the cages C are freely rotatable with respect to the forks 50 and 51 upward movement of the forks is 55 imparted to the cages since the cages present a shoulder between the main portion thereof and the reduced portion c and since this shoulder is engageable with the arms of the forks. 60 Means is provided for periodically, that is at predetermined and regular intervals, imparting lifting movement to the lifting rods 40 and 41 and preferably includes a rotating cam disk 60 mounted for rotary movement 65 on the frame 15 and having a cam lug 61 se-

cured to the upper face thereof and periodically and successively engageable with lifting toes 62 and 63 adjustably secured by means of nuts 64 and 65 to the upper ends of the long arms 42 and 44, respectively of 70 lifting rods 40 and 41.

Speed reduction gearing is provided for driving the rotatable cam disk 60 from the driving pulley 33 and this speed reduction gearing preferably includes a small pulley 75 66 fixed to the axis or shaft of the driving pulley 33 and driving a large pulley 67 by means of a belt 68 the large pulley 67 being rotatably mounted upon an arm 69 extending laterally from the frame and this large 80 pulley 67 having fixed thereto a small pulley 70 which in turn drives the rotating cam disk 60, the cam disk 60 being larger than the small pulley 70 and being driven from this small pulley by means of a belt 71 which is trained over the small pulley 70 and which operates in the peripheral groove 60^a provided in the rotating cam disk 60. The ratio between the pulleys of the reduction 85 gearing may be varied as desired to secure 90 the proper lift of the valve cages at the proper intervals and in the form shown it being adapted to meet certain requirements, the ratio is approximately 7 to 1.

In the operation of the valve grinder the 95 cam disk 60 has a continuous rotary motion, it being driven from the driving pulley 33 by the speed reduction gearing above described. At one time during the revolution of the disk 60 its camming lug 61 engages 100 the lift toe 62 and raises the lift rod 40 whereby the valve cage C engaged by the fork 50 is also raised thus permitting the valve V to partake of its oscillating movement or a portion of its oscillating movement dependent upon the ratio between the rate of oscillation of the spindle and rate 105 of rotation of the cam disk 60. As soon as the camming lug 61 disengages the lifting toe 62 the weight of the lift rod 40 and associated parts returns the lift rod to its lowermost position so that the cage C again engages the valve V. This gravity return of the lift rod does not however subject the cage and valve or the machine to any shocks 110 as the buffer spring 46 retards and cushions this return movement in its final phases. At another time in the rotation of the camming disk 60 its camming lug 61 engages 115 the lifting toe 63 and raises the lifting rod 41 in precisely the manner in which the lifting rod 40 has been raised.

It is to be understood that while one speed ratio has been shown as subsisting between the driving pulley 33 and the rotating cam 125 disk 60 this ratio may be changed as desired and such change is contemplated in order to meet various demands. It is obvious also that the rate of oscillation of the spindles may be varied by adjusting the op- 130

erating mechanism or by imparting higher or lower rate of rotation to the driving pulley 33.

I claim:

5 1. A valve grinding apparatus for use with valve assemblies including a valve cage and a valve loosely mounted in said cage, comprising a frame, vertical spindles journaled in said frame, chucks carried at the 10 lower ends of said spindles and adapted to grip the valve stems, means for oscillating said spindles and means for periodically disengaging the cages from said valves.

15 2. A valve grinding apparatus for use with valve assemblies including a valve cage and a valve loosely mounted in said cage, comprising a frame, vertical spindles journaled in said frame, chucks carried at the 20 lower ends of said spindles and adapted to grip the valve stems, means for oscillating said spindles and means for periodically disengaging the cages from said valves including vertically reciprocal rods having forks engageable with said cages.

25 3. A valve grinding apparatus for use with valve assemblies including a valve cage and a valve loosely mounted in said cage, comprising a frame, vertical spindles journaled in said frame, chucks carried at the 30 lower ends of said spindles and adapted to grip the valve stems, means for oscillating said spindles, means for periodically disengaging the cages from said valves including vertically reciprocal rods having forks engageable with said cages, and spring means 35 for cushioning the return movement of said rods.

4. A valve grinding apparatus for use with valve assemblies including a valve cage and a valve loosely mounted in said cage, comprising a frame, vertical spindles journaled in said frame, chucks carried at the lower ends of said spindles and adapted to grip the valve stems, means for oscillating said spindles including a driving pulley and motion transmission means between said pulley and said spindle, means for periodically disengaging the cage from the valve including vertically reciprocal rods having bifurcated upper ends slidably mounted in the frame, said bifurcated upper ends each including a long arm and a short arm, a lifting fork adjustably secured on the lower end of each lifting rod and engageable 50 with the adjacent valve cage, a lifting toe secured to the upper end of each of the long arms of said lift rods, a rotatable cam disk having a camming lug engageable with said lifting toes, gearing for driving said cam

disk from said driving pulley and buffer springs for cushioning downward movement of said lift rods.

5. A valve grinding apparatus for use with valve assemblies including a valve cage and a valve loosely mounted in said cage, comprising a frame, vertical spindles journaled in said frame, chucks carried at the lower ends of said spindles and adapted to grip the valve stems, means for oscillating said spindles including a driving pulley, motion transmission means between said pulley and said spindle, means for periodically disengaging the cage from the valve including vertical reciprocal rods having bifurcated upper ends slidably mounted in the frame, 75 said bifurcated upper ends each including a long arm and a short arm, a lifting fork adjustably secured on the lower end of each lifting rod and engageable with the adjacent valve cage, a lifting toe secured to the upper end of each of the long arms of said lift rods, a rotating camming disk having a camming lug engageable with said lifting toes, gearing for driving said cam disk from said driving pulley.

6. A valve grinding machine comprising a pair of standards, a frame adjustably mounted on said standards, a plurality of vertical spindles journaled in said frame, means for oscillating said spindles including a crank arm fixed to one of said spindles, a rocking arm fixed to the other of said spindles, a link connecting said crank arm and said rock arm, a driving pulley having a crank pin and a connecting rod between the 95 crank pin and the rock arm, chucks carried by the lower end of said spindles and adapted to grip the valve stems and hold the same suspended with the valve cages loosely engaged from the valves, and means for periodically lifting the valve cages including lift rods mounted for reciprocatory movement on said frame, lifting forks carried by said rods and engageable with the valve cages, lifting toes carried by the upper ends 100 of said lift rods, a rotatable cam disk journaled on said disk between said spindles and having a camming lug successively engageable with said lifting toes and gearing for driving said disk from said driving pulley. 110

7. A valve grinding apparatus including a plurality of vertical spindles, chucks carried by said spindles and adapted to engage the stems of the valves, means for oscillating said spindles, and means engageable with 115 the cages for periodically disengaging the cages from the valves.

FERNANDO JOHN DERIFIELD.
